(57) **CLAIM**

The ornamental design for a container pack, as shown and described.

DESCRIPTION

FIG. 1 is a perspective view of a container pack in accordance with my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The details shown in generally short-dashed broken lines show unclaimed subject matter only and form no part of the claimed design.

The rounded shape shown in generally long-dashed broken lines (--) in FIG. 7 represents a perforation portion and is part of the claimed design.

1 Claim, 7 Drawing Sheets
